Primary Examiner — Mary Ann Calabrese(74) Attorney, Agent, or Firm — Morgan, Lewis & Bockius LLP(57) CLAIM

The ornamental design of typeface of Chinese characters, as shown and described.

DESCRIPTION

FIGS. 1 through 9 are a face view of a typeface of Chinese characters showing my new design, to be used on printed matters or screen/monitor;

FIG. 10 is a drawing of an example of sentence; and,
FIG. 11 is an enlarged face view of a represented sample characters.

1 Claim, 11 Drawing Sheets

街佳假價加可家歌各
脚角干看間渴感敢減
甘甲強江講降個改皆
開客更去居巨舉車乾
健堅犬見決潔結京庚
慶敬景競經耕輕驚季
溪界癸計鷄古告固故
考苦高谷曲穀困坤骨
公共功工空果科課過
官觀關光廣交教校橋
久九口句救求究舊國
君軍郡弓勸卷權歸貴

FIG.1

街佳假價加可家歌各
脚角干看間渴感敢減
甘甲強江講降個改皆
開客更去居巨舉車乾
健堅犬見決潔結京庚
慶敬景競經耕輕驚季
溪界癸計鷄古告固故
考苦高谷曲穀困坤骨
公共功工空果科課過
官觀關光廣交教校橋
久九口句救求究舊國
君軍郡弓勸卷權歸貴

FIG.2

均極勤根近今禁金及
急給其基己幾技旣期
氣記起吉暖難南男乃
內女年念怒農能多丹
但單短端達談答堂當
代大對待德刀到圖島
度徒道都獨讀冬動同
東桐童斗豆頭得燈登
等樂落卵浪郎來冷兩
涼良量旅力歷練蓮列
烈令領例禮勞老路露
綠論料柳流留六陸倫

FIG.3

律利李理異林立馬莫
晚謫萬末亡忘忙望每
買賣妹麥免勉眠面名
命明鳴暮母毛木目卯
妙務戊武無舞茂墨問
文聞門勿物味星未未
美民密朴半反飯發房
放方訪防拜杯白百番
伐凡法變別丙兵病保
報步祫復服福本奉逢
部否夫婦富扶浮父北
分不佛明備悲比非飛

FIG.4

鼻貧永事仕使史四士
寺射已師思死私絲舍
謝算山散產殺三上傷
商喪尚常想相賞霜色
生序暑書西夕席惜昔
石仙先善線船選鮮舌
設說雪城姓性成星盛
省聖聲誠世勢歲洗稅
細小少所诮笑素俗續
速孫松送修受壽守愁
手授收數樹水秀雖須
首誰叔宿淑純順戊崇

FIG.5

拾習乘勝承始市施是
時示視試詩式植識食
信新申神臣身辛失室
實心深甚十氏兒我惡
安案眼顏巖暗仰哀愛
也夜野弱約若藥楊詳
羊讓陽養於漁語魚億
憶言嚴業余如汝與餘
亦易逆然煙研悅熱炎
葉榮永英迎藝五午吾
悟烏誤屋玉溫瓦臥完
日往王外要欲浴勇容

FIG.6

用于又友右宇尤憂牛
遇雨云運雲雄元原圓
園怨遠願月位偉危威
爲唯幼有柔油猶由遊
遺酉肉育恩銀乙吟陰
音飲泣邑應依意矣義
衣議醫二以已異移而
耳益認人仁印因寅引
忍一日壬入姊子字慈
者自作昨場壯將章長
哉在才材裁財再爭低
著貯寧敵的赤適傳全典

FIG. 7

前展戰田錢電節絕店
接丁井停定庭情政正
淨精貞靜頂帝弟祭第
製諸除題兆助早朝祖
調造鳥族足存尊卒鐘
宗從種終坐左罪主住
宙畫朱注走酒竹中衆
重卽增曾證之只地志
持指支柱止知紙至直
盡真辰進質執集且借
次此着察參唱昌窓採
菜冊責妻處尺千天川

FIG.8

泉凌鐵晴清聽請青體
初招草寸村最推秋追
丑祝春出充忠靈取吹
就治致齒則親士針快
他打脫探太泰宅土統
通退投特波被判八敗
貝便片篇平開佈抱暴
表品豐風彼皮匹父筆
下何夏河賀學寒恨漢
閑限韓含恒亥害海解
幸行鄉香向虛許革現
賢血協兄刑形惠乎呼

FIG. 9

好戶虎號湖或婚混紅
化和火畫花華話貨患
歡話皇黃回會孝效厚
後訓休凶胸黑興喜希

FIG.10

天地之道一陰
陽五行而已
坤復之間爲太極
而動靜之後爲
陰陽

天地之道一陰陽五行而已
坤復之間爲太極
而動靜之後爲陰陽

FIG. 11
